LUDWIG MAURER, OF NUERMBERG, GERMANY, ASSIGNOR TO NÜRNBERGER MOTORFAHRZENGE FABRIK "UNION" G. M. B. H., OF NUERMBERG, BAVARIA, GERMANY.

DEVICE FOR THROWING MOTORS INTO GEAR.

SPECIFICATION forming part of Letters Patent No. 722,122, dated March 3, 1903.

Application filed May 15, 1902. Serial No. 107,445. (No model.)

To all whom it may concern:

Be it known that I, LUDWIG MAURER, a subject of the Emperor of Germany, and a resident of Nuremberg, Bavaria, Germany, have 5 invented certain new and useful Improvements in Devices for Throwing Motors Into and Out of Gear, of which the following is a specification.

This invention has for its object a device 10 for throwing into gear the driving mechanism of motor-cars, which mechanism is constituted by a friction-wheel gear. This improved arrangement, by means of which the device for throwing into gear is specially adapted for 15 the purpose for which it is used, consists in the motor-shaft on one end of which the friction-disk is fixed being mounted so as to be capable of being displaced and being engaged at the other end by the lever for throwing 20 into gear, by means of which the motor-shaft is displaced axially, and thereby the friction-disk pressed against the friction-wheel revolutely mounted in front of it.

The improved arrangement for throwing 25 into gear is shown in one form of construction in the accompanying drawing, in which said figure represents a plan view partly in section.

A crank-shaft *b* is revolutely and, within 30 certain limits, adjustably mounted in the motor-casing *a*. On one end of the crank-shaft a friction-disk *c* is fixed, which stands closely opposite an adjustable friction-wheel *d*, mounted on a revolvable shaft *k*. At the other 35 end the crank-shaft *b* is revolutely engaged by a lever *e* for throwing the mechanism into gear, and this engagement is effected in the ordinary manner by means of a collar sliding in a sleeve *f*, on which is a pin *g*, engaging in 40 a suitable slot in the lever *e*. The engage-

ment-lever *e* is pivotally mounted at one end on the car-frame *h* and at the other end is connected by means of a suitable link-bar *i* with a handle arranged in proximity to the driver's seat in such a way that by pulling 45 the handle the lever *e* is moved to the right from its position shown in the drawing, and thereby the motor-shaft *b* is axially displaced. Consequently the friction-disk *c* comes in contact with the friction-wheel *d* and when the 50 lever *e* is firmly pulled is pressed against the said wheel, so that the rotation imparted to it by the motor is transmitted to the revolvable axle *k* of the friction-wheel, and thus to the rear-wheel axle of the motor-car. On the 55 rod *e* being released the pressure on the friction-surfaces ceases, and the driving connection between the motor and the rear-wheel axle is interrupted.

I declare that what I claim is—

In a device for throwing motor-shafts into and out of gear in motor-vehicles and the like, the combination with suitable supporting-bearings, of a motor-shaft journaled therein, having an elongated crank portion 65 and having limited endwise movement, a pitman connected to said crank to have sliding movement thereon, a friction-disk carried on the end of said shaft, a lever for moving said shaft longitudinally, and a friction-wheel adjacent to said friction-disk and adapted to be engaged and disengaged by the movement of the shaft and disk, substantially as described.

In witness whereof I have hereunto set my hand in presence of two witnesses.

LUDWIG MAURER.
